UNITED STATES PATENT OFFICE.

EDWARD W. HADLEY, OF NEW BRITAIN, CONNECTICUT, ASSIGNOR TO R. A. MOORE, SR., AND R. A. MOORE, JR., OF KENSINGTON, CONNECTICUT.

BUCKLE.

SPECIFICATION forming part of Letters Patent No. 717,743, dated January 6, 1903.

Application filed October 13, 1902. Serial No. 127,004. (No model.)

To all whom it may concern:

Be it known that I, EDWARD W. HADLEY, a citizen of the United States, residing at New Britain, in the county of Hartford and State of Connecticut, have invented certain new and useful Improvements in Buckles, of which the following is a specification.

My invention relates to improvements in buckles of the class in which a lever-jaw is pivoted to the frame and acts against a back bar thereof; and the objects of my improvement are simplicity and economy in construction and efficiency in use.

In the accompanying drawings, Figure 1 is a front elevation of my buckle, together with a portion of suspender-webbing. Fig. 2 is a sectional side elevation of the same, in which a portion of the frame is sectioned on the line *xx* of Fig. 1. Fig. 3 is a front elevation of 20 the blank for the frame or what may be said to be the frame in its flat form. Fig. 4 is a front elevation of the buckle with the handle portion of the lever-jaw turned upwardly.

I make the frame of my buckle of a single piece of wire, which is preferably first bent into substantially the form shown in Fig. 3, the same consisting of the upper and lower cross-bars 5 6 and two connecting end portions bent inwardly, as shown, so as to form 30 the two lever-bearings 7, that are parallel to the upper cross-bar 5, and the two oblique portions 8, extending from the inner ends of the lever-bearings 7 downwardly and outwardly to meet the ends of the lower cross-bar 6 by a proper curve at the junction of the said oblique portions and lower cross-bar. I prefer to first form this frame in this form, with the several members all in one plane—that is, the blank is flat. I then bend the 40 frame-blank substantially in the line of the lever-bearings 7 to bring the upper cross-bar 5 into one plane with the lever-bearings 7 7 and the body of the frame—that is, the lower cross-bar 6, oblique portions 8 8, and lever-bearings 7 7—into another plane at substantially a right angle to the said first plane, thereby giving the buckle-frame substantially an L-shaped form, as shown in Fig. 2, with the lever-bearings at the junction of the 45 said two planes or two members of the said L-shaped form.

The lever-jaw is substantially of an ordinary construction, consisting of the jaw portion 9, having preferably a toothed edge and a handle or lever portion 10, the same being 55 hinged or pivoted on the frame by rolling the eyes 11 around the lever-bearing portions 7, as best shown in Fig. 4.

A designates a portion of a suspender-webbing, with a loop 12 formed at its lower end, 60 the object of adjusting the buckle on the webbing being to vary the length of the said loop 12, as in other suspenders of this class. One end of the webbing is secured to the buckle-frame in any proper manner and the 65 other end threaded through the frame by passing in front of the lower cross-bar 6, then back of the oblique and lever-bearing portions, and then upwardly between the lever-jaw and the upper cross-bar 5. In Fig. 2 I 70 have shown the upper end of one member of the said loop 12 with the webbing passed around the bars 5 and 6 and connected on by sewing.

The particular manner of securing the webbing to the buckle and the particular part of the buckle to which the webbing is attached is only a matter of choice on the part of the suspender-manufacturer or other person who may attach the buckle to some other article, 80 the construction of the buckle and the proportions and disposition of the jaw portion of the lever-jaw to the other parts of the buckle not being in any way affected by the manner of attaching the webbing. When 85 the end of the webbing is secured to the buckle-frame by passing around both of the cross-bars 5 and 6 in the particular manner clearly shown in Fig. 2, the back of the buckle-frame is covered by the webbing, so that 90 no part of the buckle will come against the garment upon which the webbing rests.

I am aware that the combination of a pivoted lever-jaw with a buckle-frame mounted thereon to engage a cross-bar of the frame is 95 old, and I hereby disclaim the same.

I claim as my invention—

A buckle consisting solely of two members, one member in the form of a rectangular frame composed of a single piece of wire, and 100 having an upper cross-bar 5 at one of its longitudinal sides, two lever-bearings 7, 7, par-

allel to the said upper cross-bar, two connecting portions 8, 8, extending outwardly and downwardly from the inner ends of the said lever-bearings, and a lower cross-bar 6 intermediate the outer ends of the said connecting portions 8, 8, and forming the other one of the longitudinal sides of the frame, the said upper cross-bar 5 and lever-bearings 7, 7, being in one plane and the said connecting portions 8, 8, lower cross-bar 6, and lever-bearings 7, 7, being in another plane at substantially right angles to the plane of the said upper cross-bar and lever-bearings, the other member of the buckle being in the form of a lever-jaw having a jaw portion 9 and a handle or lever portion 10, standing substantially at

right angles to each other and also having a pivoted part by which it is pivoted to the said lever-bearings 7, 7, at the junction of the aforesaid two planes in which the wire frame is disposed, whereby the buckle is adapted to have the webbing or strap secured thereby, pass through the wire frame in front of both the upper and lower cross-bars thereof, and in rear of the lever-bearings 7, 7, and connecting portions 8, 8, substantially as described.

EDWARD W. HADLEY.
